(57) **CLAIM**

The ornamental design for a foldable and extendable electronic device, as shown and described.

DESCRIPTION

FIG. 1 is a perspective view of a foldable and extendable electronic device in a completely unfolded and completely extended state, showing our new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top plan view of FIG. 1;

FIG. 7 is a bottom plan view of FIG. 1;

FIG. 8 is a perspective view of the foldable and extendable electronic device of FIG. 1 in a completely unextended and completely folded state;

FIG. 9 is a front view of FIG. 8;

FIG. 10 is a rear view of FIG. 8;

FIG. 11 is a left side view of FIG. 8;

FIG. 12 is a right side view of FIG. 8;

FIG. 13 is a top plan view of FIG. 8;

FIG. 14 is a bottom plan view of FIG. 8;

FIG. 15 is a perspective view of the foldable and extendable electronic device of FIG. 1 in a completely extended and completely folded state;

FIG. 16 is a front view of FIG. 15;

FIG. 17 is a rear view of FIG. 15;

FIG. 18 is a left side view of FIG. 15;

FIG. 19 is a right side view of FIG. 15;

FIG. 20 is a top plan view of FIG. 15;

FIG. 21 is a bottom plan view of FIG. 15;

FIG. 22 is a perspective view of the foldable and extendable electronic device of FIG. 1 in a completely unextended and completely unfolded state;

FIG. 23 is a front view of FIG. 22;

FIG. 24 is a rear view of FIG. 22;

FIG. 25 is a left side view of FIG. 22;

FIG. 26 is a right side view of FIG. 22;

FIG. 27 is a top plan view of FIG. 22; and,

FIG. 28 is a bottom plan view of FIG. 22.

The broken lines in the drawings depict portions of the foldable and extendable electronic device and form no part of the claimed design.
